MARGINING DEVICE FOR USE IN
POSITIVE PRINTING

Julien Tessier, Clamart, France

Application March 5, 1947, Serial No. 732,517
In France March 5, 1946

4 Claims. (Cl. 33—184.5)

1

Margining devices as used in the printing of full-size or enlarged positives and the like consist of a frame whose masks are constituted by two adjacent sides movable with respect to the fixed sides along graduated bars to provide for accurate adjustment and by bars movable with respect to said frame for the adjustment of the margin.

My invention is concerned with various improvements made in such margining devices for the purpose of making them handier in use and more accurate in adjustment.

A first improvement concerns the mechanism for the adjustment of the movable bars designed to determine the margin of the print; said mechanism, which is mounted on a base plate, is primarily composed of a parallelogram fixedly pivoted to the base plate at two adjacent apices and to a bar movable from the outside at its two other apices; one of the links of this parallelogram is operatively connected through a link to one arm of a bell-crank lever pivoted to the base-plate and whose other arm carries a pin projecting through an arcuate aperture in said base-plate; the actuated arm of the bell-crank lever is also operatively connected with the corresponding arms of a pair of similar bell-crank levers.

Said bell-crank levers serve to transmit the displacement imparted to the bar with the aid of a screw; the pins secured on the first-mentioned pair of bell-crank levers and projecting through the aforesaid arcuate apertures are pivotally connected with a bar below the base-plate whose edge constitutes the stop line for one side of the print.

Secured to one arm of the third bell-crank lever is a pin which projects through a similar arcuate aperture in the base-plate at right angles to the first-mentioned ones; said pin is pivotally connected with one arm of a bell-crank lever similar to the ones already mentioned by a bar whose edge constitutes the stop line for another side of the print at right angles to the first-mentioned one.

The other arms of the third and the fourth bell-crank levers are pivotally interconnected by a bar or link.

Adjacent e. g. to the third bell-crank lever is provided a scale on which the set value of the margin can be read; the margining is effectuated automatically in both dimensions of the print, the two stop bars being displaced synchronously towards or from the internal edges of the mask-frame resting on the print by revolving an operating screw.

2

Another feature of my invention resides in that the bell-crank levers and the parallelogram mounted on the base-plate are enclosed in a stationary casing; the mechanism thus shielded is actuated by means of a screw projecting through a hole threaded in the side wall of the stationary casing, whose outer end carries an operating knob and whose inner end engages one side of the parallelogram.

10 Another feature of my invention resides in that those parts of the mechanism which are pivoted on the base-plate are mounted on fulcrum pins set in by riveting or otherwise secured to the base-plate and serving at the same time to locate and fix inside the stationary frame the base plate carrying the assembled mechanism with the aid of a few screws driven thereinto through the top of the casing.

15 Another feature of my invention resides in the provision of a coil or like spring adapted to keep the mechanism in the adjusted position by counteracting any backlash in the mechanism contrawise to the adjusting screw.

20 Another feature of my invention resides in the provision of a stay bar pivoted at a point of its length to one side of the frame hinged to the stationary casing, which bar is formed at one end in the shape of a hook adapted to cooperate with a stud on said stationary casing to keep the frame in its raised position to allow adjusting the position of the stop bars and locating the prints.

25 Still another feature of the invention resides in the provision of a short propping bar pivoted to one side of the frame, provided with an operating knob and adapted to keep the frame in a lower position.

30 Other features and advantages of my margining device will be pointed out in the following description of a preferred embodiment of the same, in the course of which reference will be had to the appended drawing in which:

35 Figure 1 is a plan view of the margining device.
Figure 2 is a side view of the same, the frame being shown in its raised position.

40 Figure 3 is a plan view of the mechanism with its stationary casing removed.

45 Fig. 4 is a vertical sectional view taken on line IV—IV in Fig. 3 and also according to line A—A of Fig. 1.

50 Fig. 5 is a vertical sectional view of the mechanism assembled and fixed inside of the stationary casing, the plane of the section being indicated by the lines B—B in Figs. 1 and 3.

55 The margining device is composed essentially

of a stationary base or casing 1 enclosing the margining mechanism carried by the base-plate 3.

Hinged at 4 to two sets of lugs projecting on top of said stationary casing is the frame 5 having the shape of a carpenter's square on whose sides 6, 7 graduated scales 8, 9 are secured or marked directly.

The frame is defined in the desired size with the aid of another pair of sides or masks 10, 11 carried by and slidably lengthwise of sides 6, 7 respectively and locked in the desired positions by screws 12.

The frame is held in raised position by means of a stay 14 pivoted on a pin 15 to the frame side 6 and formed at its remote end 16 with a notch designed to cooperate with a stud 17 carried by the casing.

The frame can be held in half-raised position by a short propping bar 18 pivoted to the frame side 6 on a pin 19 provided with an operating knob.

The mechanism for the accurate and quick adjustment of the margin size is as follows (Figs 3 to 5):

A base plate 3 is cut out as illustrated in Fig. 3 to fit inside of the stationary casing 1 and carries centrally threaded fulcrum pins 21, 22, 23, 24 into which fastening screws 25, 26, 27, etc., are secured through the top of the casing enclosing and locating the mechanism in the space delimited between said top and base plate 3 and leaving under said plate another space for moving the stop bars 37 and 50 through the action of said mechanism.

Mounted on the fulcrum pins 24 are a pair of links 28, 29 which, in association with a bar 30, constitute a parallelogram; the bar 30 can be acted upon with the aid of a screw 31 threaded through a hole tapped in the stationary casing. The action upon bar 30 is transmitted through the link 29 and a connecting bar 32 to one arm of a bell-crank lever 34 pivoted at 23 and whose other arm carries a pin 35 projecting through an arcuate aperture 36 milled in the base-plate; pivotally secured to said pin below the base-plate 3 in a bar 37 providing one of the print squaring side stops.

Mounted on fulcrum pin 22 at some distance from the bell-crank lever 34 is a similar bell-crank lever 38 whose pin 39 projects likewise through an arcuate aperture 49 in the base-plate below which the other end of the bar 37 is pivotally connected with said pin 39.

A helical-spring 40, as seen in Fig. 3, has one end fastened to the base 3 and its other end fastened to an arm 41 of the bell-crank 38. Parts hereinafter described cause the arm 41 to be moved when the screw 31 is operated. The spring therefore moves the arm 41 in opposition to that of the pressure screw 31 and also eliminates play in the various pivotal connections of the parts.

The arm 41 of the bell-crank lever 38 is pivotally connected with a coupling bar 42 connecting the arm 43 of bell-crank lever 34 with the arm 43 of a bell-crank lever 44 associated with a similar bell-crank lever 45; the fulcrums of bell-crank levers 44 and 45 are located on a line at right angles to the line through 22 and 23 and are constituted by centrally threaded fulcrum pins 21 which at the same time serve to maintain and locate the base plate 3 carrying the mechanism inside the stationary casing 1.

The arms 43 and 46 of the bell-crank levers 75

44 and 45 carry pins projecting through arcuate apertures 47, 48 cut in the base-plate at right angles to apertures 36, 49; pivotally secured to the ends of said pins below the base-plate 3 is a bar 50 at right angles to bar 42. The other arms of the bell-crank levers 44, 45 are interconnected by a coupling bar 51.

Graduated on a portion of the plate 3 projecting to the outside of the stationary casing 1 adjacent to the slot 47 is a scale 53.

It will be appreciated that with this mechanism any deformation of the parallelogram 24, 28, 29, 30 by the action of the screw 31 results in synchronous displacements of the stop bars 37 and 50 by the action of the two sets of bell-crank levers 34, 38, 44, 45, which displacements are exactly indicated on the scale 53.

The operation of this margining device is as follows:

After the masks 10 and 11 have been correctly positioned with respect to the graduations on scales 8 and 9 the frame is raised and held in its new position with the aid of the stay 14 or the propping bar 18, whereafter the screw 31 is actuated to adjust the margin width as desired by reference to the scale 53, the sheet of printing paper is laid in with two edges thereof exactly abutting the stop bars 37 and 50 and the frame is dropped again.

It is to be understood that the invention is by no means limited to the embodiment described hereinbefore merely by way of example, and that modifications may be made in the arrangement of the mechanism, the mounting of the parts on the base-plate, the connection of the cover plate with said base-plate, the connection of the cover plate with said base-plate, etc., without thereby departing from the scope of the invention.

What I claim as my invention and desire to secure by Letters Patent is:

1. A margining device for use in positive printing of the type comprising a rectangular frame providing a mask, two adjacent sides of which 6, 7 constitute a rigid unit similar to a carpenter's square, two graduated rails 8, 9 respectively fastened to said two adjacent sides 6, 7, the two other sides 10, 11 being adjustable by sliding on the graduated rails 8, 9 along the two first sides as desired, and a pair of horizontal margining stop bars 50, 37 parallel respectively with either side 6, 7 of said rigid unit and horizontally adjustable perpendicularly to their direction as desired, in combination with a stationary casing 1 to which one 7 of the first sides of said rigid unit is hinged on a horizontal line, means 14, 18 to support said rigid unit in at least one raised position around said horizontal line and in dropped position as desired, a movement transmitting mechanism housed inside of the stationary casing 1, and operatively associated with both margining stop bars 50—37 to provide for adjustment of said stop bars horizontally simultaneously in parallel motion towards the center of the mask 6, 7, 10, 11 or outward and means to actuate said mechanism.

2. A margining device for use in positive printing of the type comprising a rectangular frame providing a mask, two adjacent sides of which 6, 7 constitute a rigid unit similar to a carpenter's square, two graduated rails 8, 9 respectively fastened to said two adjacent sides 6, 7, the two other sides 10, 11 being adjustable by sliding on the graduated rails 8, 9 along the two first sides as desired and a pair of horizontal margining stop bars 50, 37 parallel respectively with either side

6, 7 of said rigid unit and horizontally adjustable perpendicularly to their direction as desired, in combination with a stationary casing 1 to which one 7 of the first sides of said rigid unit is hinged on a horizontal line, a stay bar 14 pivoted to the other side of the said rigid unit and adapted to be removably anchored to said stationary casing 1 for the purpose of keeping said rigid unit in raised or dropped position as desired, a movement transmitting mechanism housed inside of the stationary casing 1, and operatively associated with both margining stop bars 50, 37 to provide for adjustment of said stop bars horizontally simultaneously in parallel motion towards the center of the mask 6, 7, 10, 11 or outward, and means to actuate said mechanism.

3. A margining device for use in positive printing of the type comprising a rectangular frame providing a mask, two adjacent sides of which 6, 7 constitute a rigid unit similar to a carpenter's square, two graduated rails 8, 9 respectively fastened to said two adjacent sides 6, 7, the two other sides 10, 11 being adjustable by sliding on the graduated rails 8, 9 along the two first sides as desired, and a pair of horizontal margining stop bars 50, 37 parallel respectively with either side 6, 7 of said rigid unit and horizontally adjustable perpendicularly to their direction as desired, in combination with a stationary casing 1 to which one 7 of the first sides of said rigid unit is hinged on a horizontal line, means 14, 18 to support said rigid unit in at least one raised position around said horizontal line and in dropped position as desired, a movement transmitting mechanism housed inside of the stationary casing 1, and operatively associated with both margining stop bars 50, 37 to provide for adjustment of said stop bars horizontally simultaneously in parallel motion towards the center of the mask 6, 7, 10, 11 or outward, said mechanism comprising a horizontal base plate 3 fixed inside of the stationary casing 1, a pair of bell-crank levers 34, 38 pivoted each on a separate pivot to said horizontal base plate and pivotally connected with that 37 of said margining stop bars which is parallel to the hinged said 7 of the rigid unit 6, 7, another pair of bell-crank levers 43, 45 pivoted to said base plate 3 and pivotally connected with the other 50 of said margining stop bars, a bar 42 coupling one arm of the levers in the first-mentioned pair with one arm of one lever in the last mentioned pair, a further bar 51 coupling the levers in the last-mentioned pair with each other, the arm lengths of these various bell-crank levers being so proportioned that either stop bar 50, 37 shall be displaced in parallel motion by an amount suitably related to the displacement of the other, an actuating lever 29 pivoted to the stationary casing 1, a link 32 connecting said lever with one of the bell-crank levers, means 31 to move the whole system of levers and bars in one or the other direction and to secure said system as desired, and a spring 40 pulling on the same in the proper direction to take up any backlash in the mechanism.

4. A margining device for use in positive printing of the type comprising a rectangular frame

providing a mask, two adjacent sides of which 6, 7 constitute a rigid unit similar to a carpenter's square, two graduated rails 8, 9 respectively fastened to said adjacent sides 6, 7, the two other sides 10, 11 being adjustable by sliding on the graduated rails 8, 9 along the two first sides as desired, and a pair of horizontal margining stop bars 50, 37 parallel respectively with either side 6, 7 of said rigid unit and horizontally adjustable perpendicularly to their direction as desired, in combination with a stationary casing 1 to which one 7 of the first sides of said rigid unit is hinged on a horizontal line, means 14, 18 to support said rigid unit in at least one raised position around said horizontal line and in dropped position as desired, a movement transmitting mechanism housed inside of the stationary casing 1 and operatively associated with both margining stop bars 50, 37 to provide for adjustment of said stop bars horizontally simultaneously in parallel motion towards the center of the mask 6, 7, 10, 11 or outwards, said mechanism comprising a horizontal base plate 3 fixed inside of the stationary casing 1, a pair of bell-crank levers 34, 38 pivoted each on a separate pivot to said horizontal base plate and pivotally connected with that 37 of said margining stop bars which is parallel to the hinged side 7 of the rigid unit 6, 7, another pair of bell-crank levers 43, 45 pivoted to said base plate 3 and pivotally connected with the other 50 of said margining stop bars, a bar 42 coupling one arm of the levers in the first-mentioned pair with one arm of one lever in the last mentioned pair, a further bar 51 coupling the levers in the last-mentioned pair with each other, the arm lengths of these various bell-crank levers being so proportioned that either stop bar 50, 37 shall be displaced in parallel motion by an amount suitably related to the displacement of the other, an actuating lever 29 pivoted to the stationary casing 1, a link 32 connecting said lever with one of the bell-crank levers, means 31 to move the whole system of levers and bars in one or the other direction and to secure said system as desired, and a spring 40 pulling on the same in the proper direction to take up any backlash in the mechanism.
